UNITED STATES PATENT OFFICE.

EZRA W. CARTER, OF COHOES, NEW YORK, ASSIGNOR OF ONE-HALF TO JOSEPH BREAULT, OF COHOES, NEW YORK.

DRAWERS.

1,006,432.

Specification of Letters Patent. Patented Oct. 17, 1911.

Application filed March 2, 1911. Serial No. 611,783.

To all whom it may concern:

Be it known that I, EZRA W. CARTER, a citizen of the United States, residing at Cohoes, in the county of Albany and State 5 of New York, have invented new and useful Improvements in Drawers, of which the following is a specification.

The present invention has reference to improvements in drawers, and it comprehends, essentially, the production of an undergarment of that general type having secured thereto a reinforced suspensory which is designed not only to serve its ordinary purpose as a sack or pocket, but also to 10 bridge and close the opening below the fastening devices.

A structural embodiment of the invention is illustrated in the accompanying drawing, wherein—

20 Figures 1 and 2 are front and rear perspective views of the improved undergarment; and Fig. 3 is a perspective view of the suspensory detached from the undergarment.

25 In said drawing, 1 designates, in a general manner, a pair of drawers of the usual construction, which are formed, as is customary, with a split front, the split resulting in the production of the halves 2 and 3. 30 The upper portions of said halves are designed to be buttoned or otherwise fastened together at their front edges as indicated by the numeral 11, while the lower portions are left free at such point, the spaces between the latter portions of said edges constituting the usual crotch opening, indicated by the numeral 4.

The suspensory element is designated generally by the numeral 5 and consists of a 40 strip or blank of suitable textile material folded transversely upon itself along its central line, as shown in Fig. 3, said strip having substantially the shape of an isosceles trapezoid. When so folded, this strip is 45 fastened against the inner surface of one of the halves, preferably the left-hand half 2, by a line of stitches 6 running along its straight or folded edge, and is positioned in such a manner that the tongue 7 formed by 50 its inclined edge and lower edge will project across and thus bridge the opening 4 so as

to close the same. The short upper edge of the folded strip is attached to the half 2 by a row or rows of stitches 8 and also to the right-hand half by the row of stitches 9, said rows of stitches being located close to and extending parallel with the corresponding edges of the strip. The stitches thus obviously serve not only to secure the strip to the garment, but also to fasten the 60 folded portions or halves of said strip together along the three edges indicated, the fourth or inclined edge of the strip being left free. If desired, the attachment of the strip to the garment may be strengthened 65 by an additional line of stitches 10 arranged parallel with the vertical row 6.

The tongue 7, as shown in Figs. 1 and 2, has a length sufficient to extend a considerable distance beyond the opening 4 and thus 70 effectually close the same. As a result, the adjacent parts of the body of the wearer will be protected and kept warm, as will be understood, and such parts will be prevented from projecting through and catching 75 in the said opening.

By providing a blank of the shape described above, and folding the same in the manner indicated, a pocket or sack will be produced whose opening or mouth is afforded by the free or unconnected inclined edges; this sack is adapted to receive the testicles, and hence constitutes the suspensory proper, the introduction of testicles therein being facilitated by the tongue formation and the 85 inclination of the edges last mentioned. Finally, the garment itself is reinforced by the attachment of the suspensory element thereto and its specific positioning.

I claim as my invention:—

90 A pair of drawers having a split front, the two halves of which are provided at the upper portions of their front edges with interengaging fastening means, the lower portions of said edges being left free to produce 95 the crotch opening therebetween, and a trapezoidal strip of textile material folded transversely upon itself, to produce a pocket between its two parts, the folded strip being arranged against the inner surface of 100 one of said halves and stitched to the same along its top and bottom edges and its line

of fold, the inclined remaining edge and a portion of said bottom edge defining between them a tongue which projects across said opening in position to close the same and which is open along the former edge to permit access to the pocket.

In testimony whereof I have hereunto set

my hand in presence of two subscribing witnesses.

EZRA W. CARTER.
